UNITED STATES PATENT OFFICE.

PHILIP HAAS, OF DAYTON, OHIO.

TANK-FLUSHING DEVICE.

1,111,744.

Specification of Letters Patent. Patented Sept. 29, 1914.

Application filed June 12, 1912. Serial No. 703,345.

To all whom it may concern:

Be it known that I, PHILIP HAAS, citizen of the United States, residing at Dayton, in the county of Montgomery and State of Ohio, have invented certain new and useful Improvements in Tank-Flushing Devices; and I do hereby declare the following to be a full, clear, and exact description of the invention, such as will enable others skilled in the art to which it appertains to make and use the same.

My present invention is an improvement on the apparatus shown in my former Patent #1,084,789, granted August 6, 1912, and consists in the novel features hereinafter described, reference being had to the accompanying drawing which shows one embodiment of the invention which I have selected for purposes of illustration, and said invention is fully disclosed in the following description and claims.

The type of apparatus shown herein and in my former application is what is termed in the art an "anti-freezing" water closet valve mechanism, a portion of the valve mechanism being located in the ground below the freezing line and provided with a drain pipe communicating from the valve mechanism to the soil pipe for draining the service pipe to the closet after the flushing of the closet so as to prevent the pipe from bursting by the freezing of water therein. The specific form of the device herein shown is, like that shown in my former patent, intended to be used with a flush tank for accumulating water in said tank when the seat is depressed, and on the release of the seat, closing the inlet from the main and discharging the accumulated water from the tank to the closet bowl for flushing purposes. Devices of this character are ordinarily installed in out-houses and other places where needed and connected directly to a water main which in most cases also supplies water to the adjacent house or houses for drinking purposes and the like. It is easily possible under such circumstances for the soil pipe to become clogged so that the water will back up in the soil pipe and bowl and by reason of the drain pipe connection between the soil pipe and the valve mechanism, and the flush pipe connection between the bowl and valve mechanism, or both, that the valve casing may be filled with contaminated water which may be

forced back into the main by the air pressure in the tank or otherwise upon the opening of the water inlet valve, a sufficient distance to find its way to an adjacent hydrant, sink or other apparatus for delivering drinking water, and thus produce sickness and possible loss of life. In the construction shown in my former patent, I provided a check valve between the drain pipe and the valve casing to prevent the contamination of the water through the drain pipe, but further investigation of the subject has shown me that even with such a construction, contamination of the water in the main may take place through the flush pipe under certain circumstances, and the object of my present invention is to positively preclude the possibility of any contamination of the water in the main and the evil consequences which would ensue from such pollution, by providing a check valve between the main and the water inlet of the valve apparatus below the connection of the drain pipe therewith so that there can be no contamination of the water in the main either from the drain pipe or flush pipe, or otherwise, and water having once passed into the valve mechanism can never find its way back into the main so as to pass to another outlet.

In the drawing I have illustrated the best form in which I have contemplated embodying my said invention and the same is set forth in the following description and claims.

In Figure 1 of the drawing, is shown a vertical section of my improved device. Fig. 2 is a section of the device on line 2-2 of Fig. 1. Fig. 3 is a detailed sectional view of a portion of the apparatus shown in Fig. 1, showing the check valve between the inlet valve and the water main in closed position.

In said drawing A is a part of the bowl of the closet and B is the seat thereof, C is the main body of the device consisting of a casting having the inlet chamber C' and the outlet chamber C², the two being divided by the partition c. The pipe a is the outlet pipe connecting the outlet chamber C² with the bowl.

The top of the chamber C² is provided with a threaded opening which is closed by a cap c', through which the valve rod D extends, the said cap being provided with a stuffing box c" preventing the egress of water

through the cap. The chamber C' of casing C is connected by a pipe e³ with a reservoir or tank (not shown).

To the bottom of the casing C is connected a pipe D' and to the lower end of said pipe is connected another valve casing E. The casing E is provided with a valve chamber E' and a drain outlet e. The partition c of the casing C has a threaded opening located directly over and in line with the pipe D' and in this opening is secured the valve chamber C³. This valve chamber C³ is open at the top and bottom and is of uniform diameter except that the upper end is flared outwardly to a slight degree.

The rod D is provided with the valve e² and when the rod is in normal position is below the lower end of the valve chamber C³. The valve e² is fitted to the interior of the valve chamber C³ and when raised to engage with said valve chamber closes the same and prevents any flow of water from the tank through the outlet chamber to the bowl. A continuation of the rod D or other connection extends downward through the pipe D' into the casing E and to its lower end is secured the valve E². This valve E² is of solid cylindrical form and works in the chamber E'. A by-pass e' extends from below to a point above the valve chamber E'. This by-pass is closed when the valve E² is in its lowest position and any upward flow of water into the inlet chamber of the casing C is prevented. The lower end of the casing E is provided with the opening e² opening into a supplemental chamber F below said casing and secured thereto. This opening is provided with a projecting collar on each side of the bottom of the casing and encircling said opening forming valve seats. The lower end of the valve E² is provided with packing e³ serving as a valve to close the opening e² when the valve E² is in its lowest position. The supplementary chamber F is provided with inwardly projecting longitudinal or vertical flanges f which serve to guide the valve F' within this chamber and permit water to flow around said valve when raised from its seat.

The bottom of the chamber F is connected with a water supply pipe G, the upper end of which is provided with a seat g for the valve F'. The lower end of the valve E² is provided with the downwardly extending rod f'. This rod is smaller than the opening in the bottom of the casing E and is capable of vertical adjustment and when the said valve E² is in its highest position will hold the said valve F' away from the opening e² in the bottom of the casing E. When the valve E² is in its lowest position and the opening e² is closed the valve F' will fall by its weight and prevent any back flow from the chamber F into the supply pipe. The stem f' at the bottom of the valve rod D will

also serve to positively push the valve F' downward should there be any resistance to its action.

The valve e² is located so that in its lowest and normal position it will be sufficiently 70 below the valve chamber C³ to permit the water in the tank to flow through the valve chamber into the outlet chamber thence to the bowl to flush the same. In case the rod D is made of a single piece the valve will be 75 secured upon it in the same position.

Any preferred form of devices may be employed to connect the valve rod with the seat whereby pressure on the seat will raise the rod and open the inlet valves F' and E' 80 and close the valve e².

The valve E' is of such length that when in its lowest position it will open the drain outlet e and when raised as described will close it. 85

In the use of devices of this character, not provided with my present invention, in case the soil pipe becomes clogged so that the sewage is not discharged, the flush water will be retained in the bowl and may even overflow the same, with the result that contaminated water passes either through the flushing valve or through the drain outlet into the pipe between the inlet valve and the flushing valve, and the water in the apparatus becomes contaminated. On the next operation of the apparatus the incoming water will mix with the polluted water and pass into the tank until arrested by the accumulated air pressure therein so that all the water in the apparatus is more or less polluted. If now, while the seat is depressed and the inlet valve held in open position, as shown in Fig. 1, a faucet connected with the water main in the adjacent yard or house is opened, 105 the water in the tank will be instantly forced outward by the air pressure in the tank and back into the main and thence to the outlet or faucet, for the reason that the connection between the inlet valve and the main is a short one, whereas the connection between the faucet and the street supply is a long pipe in which the movement of the water is resisted by friction with the pipe and the pressures being equal in the tank and main 110 on the opening of a faucet in the immediate vicinity of the closet, the water will be discharged from the tank instead of the main if the seat is occupied and the inlet valve opened. According to my invention, however, this pollution of the water delivered from an adjacent faucet is absolutely prevented no matter how the pollution of the water within the closet system may have occurred, because immediately upon the ceasing of flow from the water main to the tank, the check valve below the inlet valve seats itself, as shown in Fig. 3, and even though the inlet valve may be held open indefinitely, 115 no water can pass from the closet system 120 125 130

back into the main under any circumstances whatsoever, and this great source of contamination of water for drinking and cooking purposes, which is liable to occur at any time adjacent to such closet installations, is positively prevented.

It will be seen that on disconnecting the rod D from its actuating connections and removing the cap e the rod and the parts 10 connected therewith can be drawn upward and removed without turning the water off as on raising the rod f' the valve F' will be raised by the pressure of the water and seat itself against the bottom of the casing 15 E, closing it against any inflow of water. This action is additional to the main function of this valve, which is to seat itself under the back pressure and prevent the return of any water from the valve mechanism 20 of the flushing apparatus to the main water supply. I do not desire to be limited to the exact form of valve F'. A ball valve with proper seats will answer the same purpose.

The slight outward flaring of the upper 25 end of the valve chamber C³ serves to facilitate the insertion of the parts removed when returning them to their proper place in the device.

What I claim and desire to secure by Letters Patent:—

1. In a flushing device for water closets, the combination with the bowl, a flushing pipe connected thereto, and an inlet valve for said flushing pipe located below the 35 bowl, said flushing pipe being provided with a drain outlet adjacent to the inlet valve, adapted to be connected to the soil pipe, of a check valve interposed between the inlet valve and the water supply for the flushing 40 pipe, and below the connection of the said drain outlet with the flushing pipe, said check valve being constructed to close under back pressure to positively prevent any contamination of the water supply from the 45 drain outlet and from the connection between the flushing pipe and bowl.

2. In a flushing device for water closets, the combination with the bowl, a flushing pipe connected thereto, and an inlet valve 50 for said flushing pipe located below the bowl, said flushing pipe being provided with a drain outlet adjacent to the inlet valve, adapted to be connected to the soil pipe, of a check valve located between the 55 inlet valve and the water supply therefor and below the connection of the drain outlet with the flushing pipe, and a valve seat

below said valve, said valve being adapted to close under back pressure to positively prevent contamination of the water in the 60 inlet pipe from the drain outlet, and from the connection of the flushing pipe with the bowl, said inlet valve being provided with a projection to engage the check valve to limit its upward movement and to positively 65 force it downward toward its seat when the inlet valve is in closed position.

3. In a flushing device for water closets, the combination with the bowl, a flushing pipe connected thereto, and an inlet valve 70 for said flushing pipe located below the bowl, said flushing pipe being provided with a drain outlet adjacent to the inlet valve, adapted to be connected to the soil pipe, of a check valve interposed between the inlet 75 valve and the water inlet pipe and located below the connection of the drain outlet with the flushing pipe, a valve seat for said check valve located between said valve and the inlet valve, and a valve seat for the 80 check valve located between it and the water supply, said inlet valve being provided with a projection for engaging the check valve and normally holding it away from the valve seat adjacent to the inlet valve and 85 for forcing it positively toward the other of said valve seats when the inlet valve is in closed position, whereby the said check valve will positively prevent contamination 90 of the water supply from the drain outlet and from the connection between the flushing pipe and the bowl.

4. In a flushing device for water closets, the combination with a flushing pipe, a tank 95 and a bowl operatively connected therewith, and valve mechanism including an inlet valve below the bowl, said flushing pipe being provided with a drain outlet adjacent to the inlet valve, of a check valve interposed between the inlet valve and the water 100 supply and located below the connection of the drain outlet with the flushing pipe, and constructed to close under back pressure to positively prevent the contamination of the water supply for the flushing device under 105 the back pressure of the tank, from the drain outlet and from the connection between the bowl and the flushing pipe.

In testimony whereof I affix my signature, in the presence of two witnesses.

PHILIP HAAS.
